Atty.

UNITED STATES PATENT OFFICE.

FREDERICK W. KRANZ, OF NEW YORK, N. Y., ASSIGNEE TO WESTERN ELECTRIC COMPANY, INCORPORATED, OF NEW YORK, N. Y., A CORPORATION OF NEW YORK.

SIGNALING BY HIGH-FREQUENCY WAVES.

Application filed September 29, 1919. Serial No. 327,050.

To all whom it may concern:

Be it known that I, FREDERICK W. KRANZ, a citizen of the United States, residing at New York, in the county of New York, 5 State of New York, have invented certain new and useful Improvements in Signaling by High-Frequency Waves, of which the following is a full, clear, concise, and exact description.

10 The present invention relates to the transmission of varying energy by high frequency waves for the purpose of signaling or the like. More particularly the invention relates to the transmission of a range of 15 comparatively low frequencies in the form of variations in a high frequency wave such as occurs in high frequency telephony. In such a system a high frequency wave is controlled for transmission by waves of 20 comparatively low frequency and the complex wave so produced is applied at the receiver to a frequency-modifying device commonly called a detector or demodulator, the purpose of which is to produce as a separate 25 component the low frequency waves which it is desired to receive. It is well known that a great number of combinations of frequencies may be produced by the detector, only some of which are desirable or necessary for signal reception. The presence of 30 frequencies other than those comprising the signal wave serves to confuse the signal and impair the quality. This is especially true in high frequency telephony since the voice 35 wave is a highly complex wave which must be reproduced to a nicety in order to obtain good quality of voice transmission. The interaction between the various frequencies in the process of detection produces 40 frequencies which lie within the range of essential voice frequencies and cannot, therefore, be eliminated by filters as can many of those which lie outside the voice frequency range. The frequencies which 45 are necessary for signal reception are those produced by the interaction between the signal modulated components and the high frequency or carrier wave used to transmit them, and it is desirable, therefore, to have 50 the frequencies thus produced greatly predominate. It has been found that the magnitude of the combination frequency produced by interaction of two waves of dif-

ferent frequencies is proportional to the product of the two waves and from this it follows that the wave of carrier frequency should be large compared with the received frequencies representing the signal modulated component, which are to interact in the detector to produce the desired signal frequencies. If this ratio is sufficiently large, the disturbing components, due to interaction between portions of the signal wave itself, will be scarcely or not at all noticeable in their effect upon the quality. 65

For controlling the high frequency wave by the signaling wave or other low frequency wave to be transmitted, a modulator is used. In general the modulator may perform several functions at the same time, 70 among which are modulation and amplification. If the modulator is adjusted to have maximum efficiency for one of these two functions, the other function is greatly diminished. Thus to modulate at its highest 75 efficiency the modulator would not amplify the separately impressed waves to any great extent and the resultant wave would be a modulated wave having a small ratio of carrier wave to modulation component. 80 If this ratio is to be large a sacrifice must be made in the efficiency of modulation. Heretofore the modulator has been adjusted to give a comparatively large ratio of carrier wave to modulated component at the 85 expense of the modulating efficiency.

The present invention comprises method and means for improving the quality of the received speech or other signal by obtaining a sufficiently large ratio of carrier wave to 90 the signal modulated component.

The invention further comprises method and means for providing an optimum ratio of carrier wave to the signal modulated component. 95

A feature of the invention is the separate supplying of the wave of carrier frequency to the system independently of the modulator. This enables the modulator to be operated at its maximum efficiency and still 100 permits any desired ratio of carrier wave to modulated component to be obtained for the detector.

Further features and objects of the invention will appear from the following description together with the accompanying 105

drawing in which Fig. 1 represents a diagrammatic circuit arrangement of a system according to the invention; Fig. 2 shows a curve representing measurements taken with apparatus according to the present invention and made use of in the system according to the present invention.

In Fig. 1 the heavy lines indicate one form of a high frequency telephone system to which the invention is applicable, and the light lines indicate accessory apparatus which may be used for measuring or testing purposes, as will be described hereinafter. The high frequency telephone line 1 is shown provided with apparatus for transmitting in one direction only, although by arrangements known to those skilled in the art, it may equally well serve for transmission in both directions and for simultaneous transmission of a plurality of high frequency waves each of which may be separately controlled by signals. One such source of high frequency waves is shown as an oscillator O of a well-known thermionic type, the frequency of which may be controlled by the variable condenser C. For controlling the high frequency wave produced by the source O, a modulator M is provided. When the switch 5 is thrown in the upper position and switch 6 is closed, voice currents are produced in the circuit including the transmitter T, battery 9, switches 5 and 6 and the primary of the coupling 10, due to speech waves being directed against the microphone. By means of the coupling 10 the speech waves are, therefore, impressed on the input circuit of the modulator M. The high frequency wave from the source O is supplied to the same input circuit through the amplifier A which may be of any suitable type, and is shown having its input circuit including an adjustable portion of the resistance included between the terminals 11 and 12 in the output circuit of the oscillator O. The wave which is amplified at A is applied through the circuit 13 to the potentiometer resistance 14 which is shown included in the input circuit of the modulator. As a result of the action of the modulator upon the two waves thus impressed upon it, a voice-modulated high frequency wave is transmitted through the coupling 15 and through the filter F₁ and the output coil 16. With the type of modulator shown, the output currents will ordinarily contain as components, a wave of the original carrier frequency and two side bands of frequencies respectively higher and lower than the carrier frequency and each having a frequency range equal to that of the voice currents applied to the coils 10. The filter F₁ is preferably so designed as to transmit only one of these side bands or one of the side bands and the carrier frequency, since both side

bands are not essential to signal reception. In the system shown it will be assumed that the filter F₁ passes only one of the side bands of frequencies, and that the modulator M is operated at its maximum efficiency for modulation. These frequencies are transmitted from the coil 16 to the conjugate coils 4 which are provided in the branch 2 leading to the line 1. For co-operating with the conjugate coils 4, a network 3 is indicated for a purpose to be described later on. A shielded transformer 25 is indicated for coupling a branch 2 to the line 1.

In addition to the modulator and the coil 16, another circuit is provided according to the invention for transmitting a wave to the line. This circuit 17 leads directly from the terminals of the potentiometer resistance 11, 12 in the output circuit of the oscillator to the potentiometer 18, which has a sliding contact 19 for enabling a portion of the resistance to be bridged across the midpoint of the coils 4. This arrangement permits a wave of the carrier frequency from the oscillator to be impressed directly on the branch 2 independently of the oscillator wave which is supplied to the modulator and permits the amplitude of the wave so applied to be regulated. By means of the conjugate connection none of the output current from the coil 16 finds its way into the circuit 17 and thereby through the amplifier to the input side of the modulator. Such a circulation of current under certain conditions would produce singing.

For signal transmission it is assumed that the switches 7 and 8 are both closed. The wave from the modulator and the wave separately impressed on the line from the oscillator, therefore, traverse the line 1 and are applied to the detector D. An artificial line 20 is indicated which would ordinarily not be used in a transmission system but which as here used simulates the characteristics of a line of any desired length in order to enable measuring or testing to be accomplished as will be described hereinafter. The waves applied at detector D produce by interaction a series of waves, one of which represents the signal component to be received. The output circuit of the detector D is shown as including a low-pass filter F₂ and a receiver R. The filter F₂ prevents the transmission to the receiver R of all frequencies higher than those comprised in the essential voice range.

If the proper ratio of carrier wave to modulated component was applied at the transmitting station, the disturbing currents produced by interaction of the frequencies comprising the voice wave will be practically negligible in their effect upon the wave which is received at R.

An advantage of supplying the carrier wave to the line at the transmitting station

instead of at the receiving station is that the line loss is substantially the same for the carrier component and the modulated component, and therefore, the proper ratio of carrier wave to modulated component, if once determined, will hold for various lengths of lines. This enables standardization of the apparatus to a greater degree than if a separate carrier wave oscillator were supplied for the receiver. Another advantage is that a single oscillator serves both to supply the modulator and to transmit some unmodulated carrier wave component.

The accessory circuits by which, according to the present invention, the proper ratio of carrier to modulated components can be determined, will now be described. With the switch 5 still in the upper position and the switch 6 open, the voice currents in the circuit of the transmitter T are impressed through the thermocouple 28, and their magnitude is indicated by the galvanometer 27. If now the switch 8 is open and the switch 21 is closed on the right, the voice-modulated current transmitted over the line 1 is received through the receiver shunt 22 by the second receiver 23. For the description of a receiver shunt of the type indicated at 22, reference may be had to the patent to Blackwell, 1,261,096, issued April 2, 1918. A separate line is shown leading directly from the circuit of microphone T to terminals of the switch 21 and including the artificial line 24. If speech waves are continually directed against the microphone T and if the switch 21 is alternately thrown to the right and to the left, the speech which is alternately heard in the receiver 23 will be that which is transmitted directly through the low frequency line from the microphone circuit and that which is transmitted by the high frequency line 1 respectively. This affords a basis of comparison as to quality between voice currents produced in the microphone circuit and voice currents reproduced by the detector D from the high frequency wave which was originally controlled by voice currents produced by the microphone T. By means of the artificial lines 20 and 24 the loudness of the speech transmitted over the two paths and received in receiver 23 may be made the same. If now the potentiometer 18, 19 is adjusted to impress a small amount of the carrier wave component on the line, it will be assumed that the quality of the speech received through the high frequency line is relatively poor. The receiver shunt is now adjusted to attenuate the voice currents so received to the point where they are just unintelligible. Also by varying the receiver shunt 22, the amount of attenuation necessary to reduce a speech wave directly transmitted from the microphone T to the receiver 23 to the point of unintelligibility, can be determined. This setting may be made,

once for all, for a series of measurements and is indicated in a diagram of Fig. 2 by the horizontal line VW. For a given setting of the potentiometer 18, 19 a reading is made of the strength of the voice currents by means of the galvanometer 27. The switch 5 is then thrown to the lower position to include the source 26 of sine waves in the circuit leading to the modulator M, and the resistance shown in the circuit of generator 26 is adjusted to give the same reading on the galvanometer as was obtained when speech waves were traversing this circuit. It should be stated that the switch 7 is open in these tests and therefore the tuned circuit including variable condenser 29 and coil 30 are included in the one side of the line 1. Coil 30 is coupled to the coil 31 in the input circuit of the amplifier 33 and a variable condenser 32 is provided for tuning the circuit of coil 31 to the same frequency as the circuit 29, 30. The output variable current circuit of the amplifier 33 contains the thermocouple 34 to which is connected the galvanometer 35. When the adjustments have been made as described, there will be impressed upon the line 1 a carrier wave from oscillator O, modulated by a pure sine wave from source 26, and the magnitudes of the carrier wave and of the modulating wave are respectively the same as those of the carrier wave and the modulating wave when speech currents were being transmitted. The purpose of substituting the sine wave generator 26 in place of the source of speech currents is to give a definite side frequency in place of a band of side frequencies, in order that the side frequency may be completely separated from the carrier frequency for purpose of measurement. The tuned circuits 29, 30 and 31, 32 are adjusted to selectively transmit the wave of carrier frequency only and a reading is made on the galvanometer 35. The tuned circuits are then adjusted to selectively transmit only the side frequency resulting from the modulation of the carrier wave by the wave from source 26. A reading is again made on the galvanometer 35. The frequency of the generator 26 is preferably at the mean speech frequency, say 1,000, and therefore, the filter F₁, if adjusted to pass only one side band of speech frequency, will also pass only one of the side frequencies present when generator 26 is being used. The ratio of the two readings thus obtained on the galvanometer 35 is an indication of the ratio of the carrier wave component impressed on the line to the modulated component impressed on the line.

1. This ratio is indicated in Fig. 2 as $\frac{C}{S}$. Since the magnitude of the wave from source 26 was adjusted to be equivalent to the voice currents from transmitter T, the ratio $\frac{C}{S}$ also indicates the ratio of the carrier

wave component to the voice modulated component of the carrier wave. Since the band filter F_1 transmits no unmodulated carrier wave, the ratio $\frac{C}{S}$ thus obtained, indicates the ratio of carrier wave to modulated component impressed on the detector D. To obtain the curve N. of Fig. 2, the ratio $\frac{C}{S}$ is plotted against the amount of attenuation necessary in the receiver shunt 22 to reduce the speech received over the high frequency channel to the point of unintelligibility. To obtain another point on the curve the potentiometer 18, 19 is adjusted to supply a larger amount of carrier wave component to the line, the artificial lines 20 and 24 are again adjusted if necessary to give the same loudness of the signal received at 23 over the high frequency line as over the low frequency line when the receiver shunt 22 is so adjusted as to give good quality to the speech transmitted over each path, the amount of attenuation necessary at 22 to reduce the intelligibility of the signal received through the high frequency channel to zero is again noted and a comparison is made and readings are taken as before to obtain the ratio $\frac{C}{S}$. By proceeding in this manner, a number of points may be found which will determine a curve such as indicated by N. Since the basis of comparison is the reproduction of voice currents by a simple receiver 23 as compared with reproduction of the same currents by the high frequency apparatus, it is evident that the curve N will never rise above the horizontal line VW. On the other hand, it may be shown that the curve is asymptotic to the line VW since the disturbing currents introduced by the detector D which are entirely absent in the case of the low frequency line, never become absolutely zero until the ratio of the unmodulated carrier to the modulated component becomes infinity. From the curve, however, it will be seen that for a ratio $\frac{C}{S}$ greater than about 4, the quality of the speech transmitted over the high frequency line approaches very closely to the quality obtained by the low frequency line, and it was found that a ratio of 5 or 6 gives practically as good quality as a ratio $\frac{C}{S}$ very much larger. In tests actually made, ratios of $\frac{C}{S}$ as high as 60 have been used without, however, increasing the quality appreciably more than for a ratio of 5. For most purposes, therefore, the ratio $\frac{C}{S}$ equal to 5, may be taken as an optimum value. This value when once determined, is applicable, as stated, to lines of various

lengths and having different attenuation constants, provided the manner of applying currents to the line is the same in all cases. This value, however, is useful, not only in systems of the particular type illustrated, but since 70 this value represents the ratio of the carrier component to the modulated component that should be impressed upon the detector, the ratio thus determined may be made use of for proportioning these quantities at a receiving station irrespective of the particular system of transmission that is used and whether the transmission system is a line or is a radio system. 75

The determination of this ratio that is used to obtain a high degree of quality of transmission is believed to be novel both as to method and to means. In view of the various applications which this invention may have in the transmission and reception of signals, it is not to be construed as limited in any way by the particular system or circuits that have been described and illustrated, but it is to be limited only by the scope of the appended claims. 80

What is claimed is.

1. In signaling by high frequency waves, the method of controlling the quality of signal reception which comprises transmitting a signal-modulated high frequency wave, independently transmitting a high frequency wave of the same frequency unmodulated and combining said signal-modulated and independently transmitted high frequency waves to produce the signal. 95

2. The method of signaling comprising generating a high frequency wave, modulating a portion of said high frequency wave, transmitting said modulated wave, and independently transmitting another portion of said high frequency wave during the whole period of said generation. 100

3. The method of signaling comprising modulating a high frequency wave, transmitting said wave and combining with said wave, a wave of said high frequency of such magnitude that the ratio of the unmodulated high frequency component to the modulated component is greater than four. 110

4. The method of signaling comprising modulating a high frequency wave, transmitting said wave and combining with said wave, a wave of said high frequency of such magnitude that the ratio of the unmodulated high frequency component to the modulated component is substantially five. 115

5. The method of determining the ratio of unmodulated carrier component to the modulated component transmitted through a high frequency telephone channel comprising measuring the strength of the voice currents used to modulate said high frequency wave, substituting for the voice currents a simple wave of equivalent energy to modulate the high frequency wave, supplying a 125

- fixed amount of unmodulated high frequency unmodulated high frequency wave in said wave to said channel and separately selecting and measuring the high frequency component and the modulated component obtained with said simple wave to determine their ratio.
6. The method of varying the quality of a speech wave transmitted by means of a high frequency wave comprising transmitting, at all times when the voice modulated wave is being transmitted and independently thereof, a controllable amount of unmodulated wave of the same high frequency.
7. The method of testing the quality of signals transmitted by high frequency waves, when various strengths of the unmodulated component of said high frequency waves are present, which comprises alternately indicating signal currents directly and using said currents to control transmission of high frequency waves, detecting said controlled waves, and then indicating said detected signals, and separately adding varying amounts of the unmodulated component to said controlled waves for the purpose of comparing the signals indicated directly with those indicated after controlling said high frequency transmission.
8. In a signaling system, a source of high frequency waves and a source of signaling currents to be transmitted by said waves, a modulator for controlling said high frequency waves in accordance with said signaling currents and a circuit for supplying, at all times when said controlling action occurs, a controllable amount of waves from said source of high frequency waves to said system independently of said modulator.
9. In a signaling system, a transmitting terminal, a modulator, a source of high frequency waves, a circuit for supplying waves from said source to said modulator, a separate circuit for supplying waves from said source to said terminal and a balanced circuit for preventing reaction upon said oscillator of currents supplied from said modulator.
10. A telephone system comprising a circuit for converting speech waves into speech currents, a circuit for converting said speech currents into variations in high frequency waves, a transmission circuit for said speech-controlled high frequency waves and a separate circuit for supplying, at all times when said converting action occurs, to said transmission circuit and independently of said converting circuit, a controllable amount of sustained waves of the said high frequency.
11. A high frequency telephone system comprising a transmission circuit, means for supplying speech-modulated high frequency waves to said circuit and other means for continuously supplying a sustained wave of said high frequency to said transmission circuit of such magnitude that the ratio of the unmodulated high frequency wave in said transmission circuit to the modulated component is greater than four.
12. A high frequency telephone system comprising a transmission circuit, means for supplying speech-modulated high frequency waves to said circuit and other means for continuously supplying a sustained wave of said high frequency to said transmission circuit of such magnitude that the ratio of the unmodulated high frequency wave in said transmission circuit to the modulated component is substantially five.
13. A telephone system comprising a sending station and a receiving station, a low frequency telephone line and a high frequency carrier telephone line connecting said stations, means at the transmitting station for transmitting speech over both of said lines, means for transmitting a controllable amount of unmodulated carrier waves over said high frequency line, and a receiver at the receiving station operable by speech currents transmitted over either of said lines.
14. In a signaling system, a source of high frequency waves, a detector for said waves and two paths connected between said source and said detector, one path including a modulator and a transmission circuit and the other path including an amplifier, a variable regulating resistance and said transmission circuit, said other path being in continuous energy flow condition.
15. The method of signaling comprising modulating a high frequency wave, transmitting the modulated wave, and simultaneously transmitting a wave of said high frequency of such magnitude that the ratio of the unmodulated high frequency component to modulation components representing either side band is greater than four.
16. The method of signaling comprising modulating a high frequency wave by a range of comparatively low frequencies, transmitting at least one of the resultant side bands of frequencies, and simultaneously transmitting an unmodulated wave of said high frequency of such magnitude that the total transmitted component of unmodulated high frequency wave is at least four times as great as the transmitted side band.
17. The method of signaling comprising modulating a high frequency wave, transmitting said wave and combining with said wave a wave of said high frequency of such magnitude that the ratio of the unmodulated high frequency component to the modulated component is between four and six.
18. The method of signaling comprising modulating a high frequency wave, transmitting said wave, and combining with said wave a wave of said high frequency of such magnitude that the ratio of the unmodulated high frequency component to the modulated component is between three and ten.

19. The method of signaling comprising generating a high frequency wave, modulating a portion of said high frequency wave, transmitting a single modulated side band 5 of said modulated wave, and independently transmitting another portion of said high frequency wave during modulation.
20. A system for determining the ratio of unmodulated carrier component to the modulated carrier component which comprises, a voice frequency source, a sine wave source for waves of the mean speech frequency, a high frequency source, a modulator, a transmission circuit, a circuit between the modulator and said transmission circuit adapted to transmit a single side band of the modulated high frequency waves, means for alternately supplying to the modulator waves of equivalent energy from said voice frequency source 15 and said sine wave source, means for supplying a predetermined amount of unmodu-

lated high frequency waves to said transmission circuit, and means for separately selecting and measuring the unmodulated high frequency wave and the modulated side band 25 component to determine their ratio.

21. The method of signaling by modulated waves which comprises generating and transmitting to a distant station a modulated wave, transmitting an independently 30 controllable unmodulated wave of the carrier frequency, controlling the transmission of the unmodulated wave independently of the modulation, and operating a single receiver by the cooperative action of the modulated and the independently transmitted unmodulated wave.

In witness whereof, I hereunto subscribe my name this 27th day of September A. D., 1919.

FREDERICK W. KRANZ.
